DEVICE FOR SECURING OARS IN A ROWBOAT

Filed April 2, 1947

UNITED STATES PATENT OFFICE

2,497,797

DEVICE FOR SECURING OARS IN A
ROWBOAT

Daniel Rogers, White Plains, N. Y.

Application April 2, 1947, Serial No. 738,880

7 Claims. (Cl. 9—1)

1

My invention relates to an improved device for securing oars in a rowboat. There are many conditions under which a rowboat must be left unattended. It may, for example, be necessary to moor the boat to a wharf or to draw it up on the bank of a pond or stream and leave it over night or for a longer period. There are many places where a boat may be left in this way without danger that the boat itself will be molested but it is usually not safe to leave loose articles, including the oars, in the boat. The oars are heavy and inconvenient to carry to a safe storage place and the general object of the invention is to provide an improved device for securing the oars in the boat so that they may be left with the boat with reasonable safety while the boat is not in use.

In the case of some rowboats, such as the lifeboats customarily supported from davits on passenger steamers, there is little or no danger that the oars will be intentionally carried away. If they are laid loosely in the boat, however, they may easily be misplaced or even thrown or dropped from the boat, particularly when the boat is launched during stormy weather. A further object of the invention is consequently to provide a device which may be locked to prevent unauthorized removal of the oars or which may be used simply to secure the oars in place but from which the oars may be easily released.

The invention will be better understood from the following description taken in connection with the accompanying drawing in which Fig. 1 is a perspective view of a pair of oars secured in a rowboat by a device constructed in accordance with the invention; Fig. 2 is a view of the securing device in position to lock a pair of oars to the rowboat seat, the latter being shown in cross section; Fig. 3 is a sectional view on the line 3—3 of Fig. 2; and Figs. 4 and 5 are perspective views of details.

Like reference characters indicate similar parts in the different figures of the drawing.

The oar-securing device of the invention includes a body portion 10 having a central top projection 11 and two hook-shaped lateral projections 12. The body with its projections is preferably formed from a flat metal sheet and may be produced by a simple stamping operation. It is preferably hardened so that it cannot be easily bent or cut and it is also preferably non-corrosive. It may be formed either of non-corrosive metal or of ordinary hardened steel which has been galvanized or otherwise treated to prevent corrosion.

2

One of the seats 13 of the rowboat 14 has a narrow slot 15 slightly larger than the cross sectional size of the projection 11 of the body 10. The openings 16 of the hook shaped projections 12 face upwardly toward the seat 13 and are slightly larger than the smallest part of an oar which is just beyond the inner end of the oar blade as indicated in Fig. 2.

In order to secure a pair of oars in a rowboat, 10 the handle ends 17 of the oars opposite the blades 18 are laid either in the bottom of the boat or on a seat adjacent to the seat 13 to which the oars are to be secured, the blades 18 being extended along the bottom of the boat under the 15 seat 13.

The smallest portions 19 of the oars just beyond the inner ends of the blades 18 are laid in the openings 16 of the lateral projections 12 of the securing device which is then raised with the 20 oars until the top projection 11 extends through the slot 15 in the seat 13 and until the hook-shaped projections 12 are close enough to the lower surface of the seat 13 to prevent removal of the oars. The oars cannot be removed lengthwise from the body 10 of the securing device 25 because both the blades 18 and the handle portions 17 of the oars are larger than the openings 16 in the hook-shaped sections 12 of the device. The body portion 10 may be provided 30 with shoulders 20 extending laterally from the lower end of the top projection 11 to limit and determine the uppermost position of the body 10 by meeting the lower surface of the seat 13. The top projection 11 of the device has a transverse opening 21 near its outer end and extending just above the upper surface of the seat 13 35 to receive a pin, padlock or the like 22 so that the body 10 cannot drop away from the seat 13 and release the oars. A metal plate 23 with a substantially flat face and having a narrow slot 24 in alignment with the slot 15 is secured by bolts 25 with its flat face flush with the upper surface of the seat. This plate 23 adds strength and prevents injury and wear by the pin or padlock 22 on the seat surface.

One of the hook-shaped projections 12 of the body 10 has an opening 26 near its outer end in which a ring 27 is inserted, the ring 26 also passing through an opening in the projecting 50 lower end of one of the bolts 25. Thus, when the oars are released by withdrawing the pin or padlock 22 and dropping the body 10, the plate including the body 10 with its top projection 11 and lateral projections 12 will remain pivotally 55 secured to the boat by the ring 26 so that it can-

not be easily mislaid but will always be readily accessible.

The invention provides a device which may be very economically produced and which may be used conveniently and effectively to secure one or more oars in a rowboat.

What I claim is:

1. The combination with a rowboat seat having an opening, of a metal oar-securing member having a top projection fitting through said opening and laterally oppositely extending hook-shaped projections with upwardly facing openings to support a pair of oars below said seat, and means engaging said top projection to secure it in the seat opening.

2. The combination with a rowboat seat having an opening, of a metal oar-securing member having a top projection fitting through said opening and a laterally extending hook-shaped projection with an upwardly facing opening to support an oar, the outer end of said hook-shaped projection being pivotally secured to said rowboat seat, and means engaging said top projection to secure it in said seat opening.

3. The combination with a rowboat seat having an opening, of a metal plate set flush into the upper surface of the seat and having an opening aligned with the seat opening, a metal oar-securing member having a top projection fitting through said openings and a laterally extending hook-shaped projection with an upwardly facing opening to support an oar, and means engaging said top projection to secure it in said seat and plate openings.

4. The combination with a rowboat seat having an opening, of a metal plate set flush into the upper surface of the seat and having an opening aligned with the seat opening, a bolt securing said plate to the seat, a metal oar-securing member having a top projection fitting through said openings and a laterally extending hook-shaped projection with an upwardly facing opening to support an oar, the outer end

of said hook shaped projection being pivotally secured to said bolt, and means engaging said top projection to secure it in said seat and plate openings.

5. A device for securing a pair of oars in a rowboat, said device including a metal body portion having a central projection with a transverse opening and oppositely extending hook-shaped lateral projections for supporting a pair of oars, and a metal plate with a substantially flat face and having an opening for said central projection, and means for securing said metal plate with its flat face flush with the upper surface of a rowboat seat.

10 6. A device for securing a pair of oars in a rowboat, said device including a metal body portion having a central projection with a transverse opening and oppositely extending hook-shaped lateral projections for supporting a pair of oars, and means for pivotally connecting the outer end of one of said lateral projections to a rowboat seat.

15 7. A device for securing a pair of oars in a rowboat, said device including a metal body portion having a central projection with an opening near its outer end and oppositely extending hook-shaped lateral projections for supporting a pair of oars, and a flat metal plate having an opening for said central projection, a bolt for securing said plate in the upper surface of a rowboat seat, one of said lateral projections having an opening near its outer end, and a ring inserted through said opening and loosely secured to said bolt.

20 35 DANIEL ROGERS.
